WILSON MCFARLANE, OF LOS ANGELES, CALIFORNIA.

INTERNAL-COMBUSTION ENGINE.

Application filed December 22, 1925. Serial No. 77,026.

This invention has to do generally with internal combustion engines, and is more particularly concerned with that type of engine wherein rotary pistons are employed.

5 It is the general object of the invention to provide an engine of high efficiency and to this end I have devised a novel association and combination of elements, but I will here discuss only briefly certain outstanding novel 10 features since most of the novelty may be more clearly presented as the detailed description progresses.

I employ a multiple piston rotor, one of the novel features of which lies in the provision of a plurality of spaced, movable connecting means between the rotor body and each piston. As a given piston passes a given point, one of the connecting means between the rotor and that piston is freed 20 from engagement with the piston, returning to engagement as soon as it has passed the given point so the following connecting means may be freed from the piston without at any time leaving the rotor and piston 25 ton entirely disconnected. The rotor body and pistons are annularly spaced so, by reason of this provision of movable connector, I am enabled to move a sliding abutment (which, in the illustrated embodiment, is 30 a sleeve) clear across the cylinder at said given point and into engagement with a stationary element located in the annular spacing between the rotor body and piston. This is in contra-distinction to the usual type of 35 rotary engine wherein the sliding abutment is thrust into end bearing with the peripheral face of the rotor body with the result that the wear between abutment and rotor rapidly develops to such an extent that compression 40 cannot be held and the efficiency of the motor rapidly drops.

On the other hand, by my arrangement, there is no necessity for wearing contact between rotor and abutment, and the wear between the abutment and cylinder casing is negligible.

In order that the pistons may be held from displacement while passing the cylinder wall aperture through which the abutment reciprocates, I provide a slidable closure or track member which is projected across this aperture when the abutment is withdrawn. The slide, when in operative position, also forms a wall at the end of the abutment sleeve during the inspiration of the charge, the charge being drawn into the sleeve for subsequent

compression by a piston therein. This piston defines one wall of the compression and explosion chamber and is reciprocated through a gear and crank-shaft connection with the rotor shaft, as are also the sleeve and slide. The compressing piston also acts as a movable end for the explosion chamber, taking the reaction of the explosion and transmitting a certain degree of useful force to its crank-shaft and hence to the rotor shaft to which said crank-shaft is connected by the gear train.

There is but little relative longitudinal movement between the abutment sleeve and its enclosed compressing piston, since the sleeve is moving to and fro longitudinally during reciprocation of said piston. The actual linear stroke of the compressing piston may therefore be exceptionally long and rapid without there being undue wear between it and its sleeve. As a consequence, the stroke of the compressing piston may be high as compared to the speed of the rotary pistons, a condition which is very desirable, as will hereinafter be made apparent.

Other objects and novel features of the invention will be set forth in the following detailed description, reference being made to the accompanying drawings, in which:

Fig. 1 is a side elevation, partly in broken away section, of an engine embodying my invention;

Fig. 2 is a longitudinal medial section on line 2—2 of Fig. 1;

Fig. 3 is a section on line 3—3 of Fig. 1;

Fig. 4 is a section on line 4—4 of Fig. 2;

Fig. 5 is a section on line 5—5 of Fig. 2;

Fig. 5^a is a section on line 5^a—5^a of Fig. 2;

Fig. 6 is a section on irregular line 6—6 of Fig. 1; and

Figs. 7 to 12, inclusive, are diagrammatic views which illustrate the relative positions of the parts during different stages of a cycle of operation.

Main casting 10 is made up of two shells 11 and 12 bolted together along their marginal flanges 13 at 14. The casting may be considered as being made up of cylinder portion 15, crank case 16, and intermediate, connecting portion 17, which latter houses the gas compressing elements. Portion 15 and casing 16 have foot or base flanges 15^a for support on and attachment to underlying structure or foundation (not shown).

Rotor shaft 18 is journaled at 18^a in portion 15, while crank-shaft 19 is journaled in

case 16 at 20. Gears 21 and 22 on shafts 18 and 19, respectively, and intermediate idler gears 23 on casting-carried stationary stub shafts 24, interconnect shafts 18 and 19, the ratio of the gears being such that the angular velocity of shaft 19 is thrice that of shaft 18. This is for the reason that the mechanism driven by shaft 19 is to have a complete operative cycle for each of the three rotary pistons A which are associated with rotor shaft 18. Of course, where there are fewer or more rotary pistons, the gear ratio will be changed accordingly. I will consider shaft 18 as the power shaft, though it will hereinafter be made apparent that shaft 19 may also deliver power.

Cylinder portion 15 defines concentric annular cylinder bore 25 and rotor compartment 26, the latter accommodating rotor disk 27, there being an annular passageway 28 between and in communication with both the bore and compartment. Bore 25, and pistons A therein, are of circular transverse cross section, and the pistons may be provided with packing or rings 29 to insure a tight fit.

It is one of the novel features of my device to provide means whereby a barrier may be projected entirely across bore 25 and into overlapping relation with a surface beyond the inner periphery of the bore, this barrier being adapted to engage one of the walls which isolates a portion of the cylinder bore during certain stages of operation. It is within this isolated portion or chamber that the explosion takes place. By providing the sealing surface between the barrier and the stationary portion of the engine in this manner and of this nature (in contradistinction to the usual construction where a barrier is moved transversely across the bore and into end contact with the periphery of the rotor, with resulting excessive wear and rapid loss of efficiency) there is very little wear on the barrier or the complementary sealing surface; and a tight joint may be preserved therebetween indefinitely, to obvious advantage.

However, the provision of a stationary sealing member between the rotor shaft and the inner side of the cylinder, presents certain inherent and peculiar problems, for the sealing member would ordinarily intercept the connecting elements between the shafts and pistons and prevent operation. I have overcome these problems in the manner outlined below.

Sealing member 30 is in the form of a cylindrical plug having a force fit within casing 10 and having an arcuate passageway 31 therethrough which is complementary to the cylinder bore. The plug is of sufficient diameter to bring its lower portion 32 into annular passageway 28, and approximately tangential with respect to rotor 27.

A barrier, preferably in the form of sleeve S is mounted for longitudinal reciprocation through horizontal bore 33 in casting portion 17, said bore opening to cylinder bore 25 at 35. The sleeve is adapted periodically to traverse the cylinder bore at this point and is axially aligned with plug 32. The sleeve is of such diameter that (when it is near the limit of its stroke to the left, as viewed in Fig. 2) it may slip over or be moved into telescopic relation with the end of the plug, casting 10 being cut away at 35 around the plug to provide a socket for receiving the sleeve end. The sleeve has a snug sliding fit around the plug end, especially at portion 32, (and it may carry packing or rings 36 to insure a tight fit) and it will be seen that it overlaps the sealing member for a considerable distance inwardly from the inner periphery of the cylinder defining wall of the casting. The sleeve, when thus projected, forms a barrier across the cylinder bore and provides the annular wall of explosion chamber E, the chamber being otherwise defined by the walls of passageway 31, the particular piston A which is in passageway 31, and compressing piston P, the latter being mounted for longitudinal reciprocation through sleeve S with which it has snug, sliding fit. Rings 37 may be provided to insure such a fit.

For the time being, I will disregard the mechanism for reciprocating sleeve S and piston P but it will be assured that the sleeve and piston have been moved to the position illustrated in Fig. 2.

Pistons A have spaced sockets 38 at their forward and rear ends, the rearward sockets being provided in noses 38a which extend ahead of the flat faces 39 of the pistons. These sockets are for the reception of connecting arms 40 which are longitudinally slidable through ways 41 in rotor 27, said ways extending substantially radially. The arms are controlled in their longitudinal movement by rollers 42 which are journaled on laterally extending stub shafts 43, as clearly shown in Fig. 3, and are adapted to roll through cam groove 44 in stationary portion 15 when the shaft and rotor are revolved.

Groove 44 is concentric with rotor 27 throughout the major portion of its extent and consequently arms 40 are held in operative engagement with pistons A throughout the major extent of their angular movement. However, groove 44 has a dip at 45, approximately opposite sealing member 32, so when a given arm approaches this portion it is drawn inwardly sufficiently to clear. However, the arm at the forward end of a given piston is returned to operative connection with said piston before the rearward arm has been retracted, so, when the piston

is passing sealing member 32, there is always at least one arm operatively connecting the piston and rotor.

From the end of plug 30 at opposite sides 5 of the orifice or mouth of passageway 31, are guide lugs 46 (Figs. 2 and 5^a) which aid in guiding pistons A as they pass opening 34 during certain stages of operation. The end of piston P has sockets 47 for the reception 10 of these lugs when the piston is near and at the end of its compression stroke.

Piston P is connected by rod 48 to counterbalanced crank 49 on shaft 19; while sleeve S is connected to crank 50, on this 15 shaft, by rod 51 (Figs. 1 and 3). The connection between the sleeve and rod is made through a sleeve-carried pin 52 which extends through bearing 53 at the end of the rod and into slide block 54 which is slidably 20 mounted within way 55.

It will be noted that cranks 49 and 50 are angularly spaced, with rod 50 in advance, and that crank 49 is somewhat longer than crank 50, or, about one-half its actual linear speed. 25 This relative speed permits the true stroke of the piston to be comparatively long, and gives it a very high speed compared with the rotary speed of pistons A. By virtue of its high comparative speed, piston P is able to 30 get close to a given piston A to compress the gas therebetween. The crank 49 for the compressing piston will be close to dead center before the piston's speed is reduced sufficiently to be substantially equal to that of the given rotary piston, approximately at which time the explosion of the compressed gases 35 is caused to occur by spark plug 56. However, this period of equal piston speed may occur when crank 49 is more than 15° from dead center and explosion occurring at this time tends to check the continued forward 40 advance of piston P; the momentum and power behind piston P (as transmitted to it from piston A through shaft 18, the gear train, shaft 19 and crank 49) carries crank 49 over dead center. After it passes dead 45 center, the expansive action of the exploded charge cause a delivery of power to shaft 19 through piston P, rod 48 and crank 49.

Plug 56 may be fired in any suitable manner. For instance timer 57, operated by 55 shaft 18 through gear train 58, may be in circuit with plug 56 and source 59 of electricity, the timer being arranged to fire the charge in chamber E as each of the rotary pistons comes into proper position.

The gas inlet to bore 33 and hence to the 60 forward end of sleeve S, is indicated at in Fig. 6, this inlet opening from chamber 61 in portion 17 of casting 10. Valved port 62 forms a communication between chambers 65 61 and 63, the latter having an opening 64

which is adapted to be in communication with a carburetor (not shown).

Valve 65 is normally held by spring 66 in a position to close port 62, the stem 65^a of the valve having a head 67 arranged exteriorly 70 of chamber 63. A lever 68 is pivoted at 69, intermediate its ends, to casing 10, one end of the lever being forked at 70 to take stem 66, and the other end 71 extending into contact with the end 72 of push or tappet rod 75 78. A cam 74 on shaft 19 is adapted, at proper intervals, to thrust rod 73 (which rod is mounted for longitudinal reciprocation in guides 75 on casting 10) to the left as viewed in Figs. 2 and 6, and thereby open valve 65 80 against the action of spring 66, admitting a charge of gas to the bore of sleeve S. When the high point of cam 74 passes from beneath rod 73, spring 66 acts to close valve 65 and to return lever 68 and rod 73 to normal. 85

A slide W is adapted to be projected periodically across bore 33 in front of sleeve S and piston P, this slide being adapted to form one wall of the gas inlet chamber otherwise defined by this sleeve and the end of 90 piston P, to provide a guide or track for pistons A as they pass opening 34, and to keep exhaust gas out of sleeve S.

Slide W is a flat member arranged at an angle with both the longitudinal and transverse axis of the sleeve, and has side tongues 76 adapted to slide through ways 77 in guides 78 on casting 10. Slide W is periodically reciprocated longitudinally by the following mechanism. A link 79 connects the 95 slide to one end of crank arm 80 on shaft 81, this shaft being mounted for oscillation in bearing 82 on casting 10 and carrying at its other end a crank arm 83. Rod 84 is pivotally connected to crank 83 and is adapted 100 to slide longitudinally through a guide block 85 which has an integral pin 86 whereby it is pivotally connected to casting 10. The pivotal mounting of the block permits the requisite angular movement of the rod. The 105 end of the rod has a member 87 from which extends a stub shaft 88 carrying roller 89, this roller being adapted to roll through cam groove 90 in disk 91 on shaft 19. The major extent 91 of groove 90 is concentric with 110 shaft 19 and, while the roller is in this extent, rod 84 holds slide W in the fully elevated position of Fig. 2. Groove 90 has a drop portion at 92, a portion at 93 concentric with shaft 19, and a lift portion at 94. As 115 roller 89 drops through portion 92, rod 84 is drawn to the right, as viewed in Fig. 2, swinging cranks 83 and 80 in a counterclockwise direction and thus projecting slide W across bore 33, where it is held as long as 120 roller 89 is in groove portion 93. As the roller travels through groove portion 94, the slide is returned to the position of Fig. 1, as 125 will be readily understood.

All the parts are relatively arranged ap- 130

proximately as shown in the drawings, and I will therefore proceed to a description of the 5 circular operation of the engine, referring for this purpose to diagrammatic Figs. 7 to 12, inclusive.

Fig. 7 shows the parts approximately in the condition of Fig. 2, at which time explosion of the charge within chamber E is about to occur, piston A' thrusting out through 10 exhaust port 95 the exhaust gases from the immediately preceding explosion. When the explosion occurs, piston A' is driven in the direction of the arrows, imparting, through arms 40, rotary movement to rotor 27 and 15 shaft 18 and thereby causing operation of shaft 19 and its associated mechanism. Sleeve S and piston P start back to clear the way for piston A'' as shown in Fig. 8, and then slide W starts down, as shown in Fig. 20 9, to guide and support piston A'' as it reaches opening 34 at the intersection of bores 25 and 33. The slide, when it is down as in Fig. 10, also forms a wall of gas chamber G, formed by sleeve S, (and the slide 25 stays full down for a short period, as explained above) and as the piston P approaches the end of its stroke (Fig. 10) cam 74 operates the inlet valve 65 to admit a charge of gas to chamber G, the charge being drawn in by further movement of piston P or being forced in under pressure by 30 means not here shown.

As the sleeve S starts back (Fig. 11) slide W is retracted to clear the way, and a little 35 later piston P starts on its return or compression stroke (Fig. 12). The piston moves forward faster than the sleeve, but the sleeve is of such length and has advanced initially to such an extent that it is projected across 40 bore 25 and into partial overlap with sealing member 32 before piston P has compressed the gas. The sleeve travels much faster than does piston A'', and "overtakes" it as its rearward end enters plug passageway 31.

45 The cycle is then repeated, the next explosion taking place approximately when pistons P and A'' are traveling at the same speed, as explained above.

It will be understood the drawings and 50 description are to be considered merely as illustrative of and not restrictive on the broader claims appended hereto, for various changes in design, structure and arrangement may be made without departing from 55 the spirit and scope of said claims.

I claim:

1. In an internal combustion engine, the combination of a cylinder having an annular bore, a rotor concentric with said bore and 60 annularly spaced therefrom, a stationary sealing member in the annular space thus defined, a piston in the cylinder, a plurality of members releasably connecting the rotor and piston and withdrawably extending 65 through said annular space, and means

adapted to withdraw each of said connecting members from the piston and space prior to its reaching said sealing member during rotation of the rotor, and to project the given connecting member across the space and into connection with the piston after the given connecting member has passed the sealing member; a least one of said connecting members always being in operative connection with the piston.

2. In an internal combustion engine, the combination of a cylinder having an annular bore, a rotor concentric with said bore and annularly spaced therefrom, a stationary sealing member in the annular space thus defined, a piston in the cylinder, a plurality of members releasably connecting the rotor and piston and withdrawably extending through said annular space, and cam means adapted to withdraw each of said connecting members from the piston and space prior to its reaching said sealing member during rotation of the rotor and to project the given connecting member across the space and into connection with the piston after the given connecting member has passed the sealing member; at least one of said connecting members always being in operative connection with the piston.

3. In an internal combustion engine, the combination of a cylinder having an annular bore, a rotor concentric with said bore and annularly spaced therefrom, a stationary sealing member in the annular space thus defined, a piston in the cylinder, a plurality of members releasably connecting the rotor and piston and withdrawably extending through said annular space, and means adapted to withdraw each of said connecting members from the piston and space prior to its reaching said sealing member during rotation of the rotor and to project the given connecting member across the space and into connection with the piston after the given connecting member has passed the sealing member; at least one of said connecting members always being in operative connection with the piston; said means embodying a relatively stationary member having a cam groove, and cam rollers on the connecting members and entered in said groove.

4. In an internal combustion engine, the combination of a cylinder having an annular bore, a rotor concentric with said bore and annularly spaced therefrom, a stationary sealing member in the annular space thus defined, a piston in the cylinder, a plurality of members releasably connecting the rotor and piston and withdrawably extending through said annular space, means adapted to withdraw each of said connecting members from the piston and space prior to its reaching said sealing member during rotation of the rotor and to project

the given connecting member across the space and into connection with the piston after the given connecting member has passed the sealing member; at least one of said connecting members always being in operative connection with the piston, and a reciprocatory abutment adapted to be projected periodically across the cylinder bore and annular space and into sealing engagement with said sealing member.

5. In an internal combustion engine, the combination of a cylinder having an annular bore, a rotor concentric with said bore and annularly spaced therefrom, a stationary sealing member in the annular space thus defined, a piston in the cylinder, a plurality of members releasably connecting the rotor and piston and withdrawably extending through said annular space, means 15 adapted to withdraw each of said connecting members from the piston and space prior to its reaching said sealing member during rotation of the rotor, and to project the given connecting member across the space 20 and into connection with the piston after the given connecting member has passed the sealing member; at least one of said connecting members always being in operative connection with the piston, a tubular reciprocatory abutment adapted to be projected periodically across the cylinder bore and annular space and into sealing engagement with said sealing member, a reciprocatory piston within the bore of the abutment, and 25 operative connections between the rotor; reciprocatory piston and abutment whereby rotation of the rotor imparts coincident reciprocatory movement to the reciprocatory piston and abutment.

40. 6. In an internal combustion engine, the combination of a cylinder having an annular bore and another cylinder having a cylindrical bore which is substantially tangential to and opens into said annular bore, a rotor concentric with said annular bore, a piston in said annular bore and operatively connected to said rotor, a longitudinally reciprocatory tubular abutment in the cylindrical bore and adapted to be projected 45 periodically across the annular bore, a longitudinally reciprocatory piston within the abutment bore, means for reciprocating the abutment and reciprocatory piston, a slide member adapted to be projected across the cylindrical bore when the abutment is retracted from the annular bore; and means for projecting and retracting said slide member.

7. In an internal combustion engine, the combination of a cylinder having an annular bore and another cylinder having a cylindrical bore which is substantially tangential to and opens into said annular bore, a rotor concentric with said annular bore, a piston in said annular bore and operatively

connected to said rotor, a longitudinally reciprocatory tubular abutment in the cylindrical bore and adapted to be projected periodically across the annular bore, a longitudinally reciprocatory piston within the abutment bore, means for reciprocating the abutment and the reciprocatory piston, a slide member adapted to be projected across the cylindrical bore when the abutment is retracted from the annular bore, and means 70 for projecting and retracting said slide member; the point at which said slide member is projected across said cylindrical bore being located approximately where said bore opens to the annular bore, whereby, when the slide member is projected, it provides a guide for the rotor piston in its rotation.

8. In an internal combustion engine, the combination of a cylinder having an annular bore, a piston in the bore, a rotor concentric with said bore and drivingly connected to the piston, said rotor being annularly spaced from said bore, a stationary sealing member in the annular space thus defined, and a reciprocating abutment adapted to be projected periodically across the cylinder bore into sealing engagement with said sealing member.

9. In an internal combustion engine, the combination of a cylinder having an annular bore, a piston in the bore, a rotor concentric with said bore and drivingly connected to the piston, said rotor being annularly spaced from said bore, a stationary sealing member projecting into the annular space thus defined, and a tubular reciprocatory abutment adapted to be projected periodically across the cylinder bore into telescopic relation with the sealing member.

10. In an internal combustion engine, the combination of a cylinder having an annular bore, a piston in the bore, a rotor concentric with said bore and drivingly connected to the piston, said rotor being annularly spaced from said bore, a tubular, stationary sealing element having a portion extending into the annular space thus defined, the bore of said sealing member comprising, in effect, a portion of said annular cylinder bore, a tubular reciprocatory abutment in alignment with an exposed end of the sealing member, said abutment being adapted to be projected periodically across the cylinder bore, said abutment and exposed end of the sealing member being of such relative size and the extent of abutment projection being such that when said abutment is projected across the cylinder bore the abutment is moved into telescopic relation with said exposed end.

11. In an internal combustion engine, the combination of a cylinder having an annular bore, a piston in the bore, a rotor concentric with the bore and drivingly connected to the piston, a reciprocatory abutment adapted to be projected periodically across the cylinder bore from one side to the other, and

- 6 a stationary sealing member at said other side of the bore, said abutment being adapted to be moved into sealing engagement with the sealing member when it is so projected. 35
- 5 12. In an internal combustion engine, the combination of a cylinder having an annular bore, a piston in the bore, a rotor concentric with the bore and drivingly connected to the piston, a reciprocatory abutment adapted 40 to be projected periodically across the cylinder bore from one side to the other, and a stationary sealing member at said other side of the bore, said abutment being adapted to be moved into telescopic relation with the 45 sealing member when it is so projected. 50
13. In an internal combustion engine, the combination of a cylinder having an annular bore, a piston in the bore, a rotor concentric with the bore and drivingly connected to the piston, a tubular reciprocatory abutment 55 adapted to be projected periodically across the cylinder bore from one side to the other, a stationary sealing member at said other side of the bore, said abutment being adapted to be moved into sealing engagement with the sealing member when it is so projected; and a reciprocatory piston in the bore of the 60 abutment. 55
14. In an internal combustion engine, the combination of a cylinder having an annular bore, a piston in the bore, a rotor concentric with the bore and drivingly connected to the piston, a reciprocatory abut- 65

ment adapted to be projected periodically across the cylinder bore from one side to the other, a stationary sealing member at said other side of the bore, said abutment being adapted to be moved into sealing engagement with the sealing member when it is so projected, and a slide member adapted to be projected between the sealing member and abutment when said abutment is out of engagement with the sealing member. 70

15. In an internal combustion engine, the combination of a cylinder having an annular bore, a piston in the bore, a rotor concentric with the bore and drivingly connected to the piston, a reciprocatory abutment adapted 75 to be projected periodically across the cylinder bore from one side to the other, means for reciprocating the abutment, a stationary sealing member at said other side of the bore, said abutment being adapted to be moved into sealing engagement with the sealing member when it is so projected; a slide member adapted to be projected between the sealing member and abutment when said abutment is out of engagement with the sealing member and means for projecting and re- 80 tracting said slide member in time with the reciprocations of said abutment. 85

In witness that I claim the foregoing I have hereunto subscribed my name this 10th day of October, 1925.

WILSON McFARLANE.
